UNITED STATES PATENT OFFICE.

THOMAS J. PEARSON, OF NEWARK, NEW JERSEY.

DESIGN FOR A HAT-TIP.

SPECIFICATION forming part of Design No. 23,944, dated January 8, 1895.

Application filed October 3, 1894. Serial No. 524,836. Term of patent 7 years.

To all whom it may concern:

Be it known that I, THOMAS J. PEARSON, a citizen of the United States, residing at Newark, in the county of Essex and State of New Jersey, have invented and produced a new and original Design for a Hat-Tip; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Referring to said drawings, Figure 1 is a plan view showing my design which is intended to be arranged centrally, either transversely or longitudinally upon the inside of the hat. Fig. 2 is a transverse section, taken on the line α of Fig. 1. These two views are deemed sufficient to fully illustrate my design.

One of the leading features of the design consists in a raised rib, a , arranged centrally, either transversely or longitudinally on the inside of the hat. Another feature is a raised annular rib arranged at the center of the design and intersecting with said longitudinal rib. At the center of the annular rib is arranged the ornament c .

The design is shown as having a plain surface.

What I claim as new is—

The design for a hat tip, as herein shown and described.

In testimony that I claim the foregoing I have hereunto set my hand this 1st day of October, 1894.

THOMAS J. PEARSON.
